 4 Claims. (Cl. 144—208)

ABSTRACT OF THE DISCLOSURE

A cutter disc and a feed roller of a barking machine are mounted on a common driven shaft. A helical rib on the roller frictionally engages a log placed on the roller to turn the log about its axis, to advance it axially, and to move it toward the cutter disc. The axial advance is controlled by a knife blade whose cutting edge engages the log at an adjustable angle to the log axis.

This invention relates to barking machines for logs, and particularly to an improved feeding arrangement in such a machine.

The barking machines known heretofore are equipped with rotary feeders which are operated by complex and costly devices. They permit a log to be fed to cutters for the bark in a forward direction only so that the spots of bark left after the first treatment cannot conveniently be worked over again.

The invention aims at providing a barking machine which avoids the shortcomings of the known devices, is simple, reliable, and inexpensive, and permits a log to be moved back and forth past the cutters as needed.

With these and other objects in view, the invention, in one of its aspects, resides in a barking machine of the type having a rotary cutter and drive means which frictionally engage a log to be barked for feeding the log lengthwise past the cutter while rotating the log about its longitudinal axis. The invention is more specifically concerned with an improved mechanism for controlling the feeding rate. It provides a knife blade which may be moved toward and away from a position of cutting engagement of its edge with the rotating log, and which is secured against rotation by this engagement. Adjusting means are provided for varying the angle defined by the edge and by the longitudinal axis of the log. The blade, the devices which secure it against rotation, and which permit the angle of the cutting edge and of the log axis to be varied are mounted on a common support with the rotary cutter and the drive means by a linkage which provides the movability of the blade toward and away from its position of cutting engagement with the log.

Other features of the invention and the attendant advantages thereof will become apparent as the disclosure proceeds.

A preferred embodiment of the invention is shown in the attached drawing in which:

FIG. 1 shows a machine of the invention in side-elevation, and partly in section;

FIG. 2 illustrates the machine of FIG. 1 in front elevation, and partly in section; and

FIG. 3 shows a portion of the apparatus of FIG. 2 on a larger scale.

The working elements of the illustrated barking machine are mounted on a supporting frame 19 and are operated by a shaft 20 journaled in bearings 7 on the frame 19. The shaft carries a conical, helically ribbed feed roller 8 and a cutter disc 11 having a conical face which tapers toward the base of the roller 8 and is provided with three equiangularly spaced, radial cutting blades 21.

A feed control mechanism mounted above the roller 8 includes a flat knife blade 10 attached to a normally upright pivot pin 22 which swivels on a bar 1. An operating handle 13 is also fixedly attached to the blade 10. The

2

handle 13 is fastened to a stationary column 4 on a transverse member 16 of the frame 19 by a telescopically extensible guide arm 3 equipped with a ball-and-socket joint 5. The joint is attached to a clamp 23 which can be shifted longitudinally on the handle 13 and arrested by means of a clamping screw 24.

The bar 1 is attached to the column 4 by means of a beam 2 and a link 15 whose ends are attached to the column 4 by pivot pins 27, 28 respectively and to the bar 1 by respective pivot pins 25, 26 so that the bar 1 may swing on the column 4 toward and away from the shaft 20 and the devices mounted thereon. The bar 1 is biased downward toward the shaft by a spring 29 whose upper end is hooked into one of several openings 30 in a bracket dependent from the beam 2, and whose lower end is attached to the frame 19. The tension of the spring may be adjusted by shifting it between the openings 30. An upright abutment rod 31 on the frame 19 limits downward movement of the bar 1 and prevents engagement of the blade 10 with the roller 8.

A fixed bracket 32 on the bar 1 carries a toothed bar 14 by means of two connected pivot pins 33, 34 whose axes are at right angles to each other, thus permitting angular movement of the bar 14 in planes which are approximately parallel to the axis of the shaft 20 and transverse of the axis. A spring 35 interposed between an arm 36 on the bar 14 and the bar 1 biases the toothed bar 14 toward the disc 11, but abutting engagement of the bar 14 with the bracket 32 prevents the bar from touching the disc.

The shaft 20 is driven by a belt trained over pulleys 9 on the shaft 20 and on a countershaft 18 which is journaled in a bearing 17 on the frame 19. The countershaft 18 is connected with a power take-off 37 on a non-illustrated tractor on which the frame is normally mounted by means of pins 38 in a conventional manner.

Sleeves 39 mounted on the frame 19 on opposite sides of the roller 8 adjustably support brackets 43, 42 which respectively support a cradle 40 and a roller 41 whose height and angular positions may be adjusted.

A non-illustrated box is normally provided under the disc 11 to collect the bark and shavings removed from a log by the blades 21, or a suction device is provided for the same purpose.

The afore-described machine is operated as follows: A log 6 which is to be barked is placed on the cradle 40 and on the roller 8 which is rotated clockwise as viewed in FIG. 2, while the log abuts against a fence 12 mounted on the bar 1. The helical rib on the roller 8 causes the log to turn about its axis and to move on the roller toward the disc 11 and into engagement with the teeth of the bar 14. Since the log turns clockwise, as viewed in FIG. 1, it lifts the bar 14 and swings the beam 2 and link 15 together with the elements supported thereon upward on the pivot pins 27, 28. The fence 12 and the knife blade 10 are raised until they clear the log 6 which can then proceed toward the disc 11 and in the direction of the arrow A (FIG. 2) under the driving force of the roller 8.

When the log 6 passes the lower end of the toothed bar 14, the bar again drops to the level illustrated in FIGS. 1 and 2. It is held against the face of the log remote from the disc 11 by the spring 35 while the bark is removed from the turning log by the revolving blades 21.

The knife blade 10 descends with the toothed bar 14 and is driven into the log 6 by the spring 29. The relationship between the rotary speed of the log and its forward speed in the direction of the arrow A is determined by the angle between the plane of the cutting edges of the knife blade 10 and the axis of the shaft 20 or the longitudinal axis of the leg 6. This angle can be adjusted by means of the operating handle 13. When a knob at

the free end of the handle 13 is pulled toward the top of the barking machine, the knife blade 10 is turned on its pivot pin 22 toward a position in which its cutting plane is parallel to the shaft 20 so that the advance of the log 6 in the direction of the arrow A is slowed. When 5 the knob on the handle 13 is pushed down toward the frame 19, the angle between the axis of the shaft 20 and the cutting plane of the knife blade 10 is increased, and so is the rate of log advance.

The angle defined by the cutting plane of the knife blade 10 and the axis of the shaft 20 or of the log 6 may also be set automatically. When the beam 2 and link 15 are lifted during engagement of a newly supplied log 6 with the toothed bar 14, as described above, the shorter link 15 pulls the lower end of the bar 1 closer to the 15 column 4 than the upper end of the bar 1 is drawn by the longer beam 2. The operating handle 13 and the attached knife blade 10 are thereby turned on the joint 5 in a direction to reduce the angle between the cutting plane of the blade 10 and the axis of the shaft 20. The 20 desired angle may be determined in advance by suitably positioning the clamp 23 on the handle 13 and by adjusting the length of the guide arm 3.

It should be understood, of course, that the foregoing disclosure relates only to a preferred embodiment of the 25 invention, and that numerous modifications may be made therein without departing from the spirit and the scope of the invention as set forth in the appended claims.

I claim:

1. In a barking machine having a rotary cutter, drive means frictionally engaging a log to be barked for feeding the log lengthwise past the cutter while rotating the log about the longitudinal axis thereof, and a feed control

mechanism for controlling the feeding rate, the improvement in the control mechanism which comprises:

- (a) a knife blade having a cutting edge;
- (b) moving means for moving the blade toward and away from a position of cutting engagement of said edge with the rotating log;
- (c) securing means securing the knife blade against rotation by said engagement; and
- (d) adjusting means for varying the angle defined by said edge and by said longitudinal axis.

2. In a machine as set forth in claim 1, a support carrying said rotary cutter, said drive means, and said mechanism, said moving means including linkage means movably mounted on said support, said blade, said securing means and said adjusting means being supported on said linkage means.

3. In a machine as set forth in claim 2, said adjusting means including means responsive to movement of said linkage means on said support in a direction for moving said blade toward said position of cutting engagement to increase said angle.

4. In a machine as set forth in claim 1, said moving means including means responsive to the approach of a log to said cutter for first moving said blade away from said position thereof and for thereafter moving the blade toward said position.
